UNITED STATES PATENT OFFICE.

WILLIAM H. SOLEY, OF PHILADELPHIA, PENNSYLVANIA, ASSIGNOR OF ONE-HALF TO THOS. H. DALLETT CO., A CORPORATION OF NEW JERSEY.

PNEUMATIC TOOL.

SPECIFICATION forming part of Letters Patent No. 755,324, dated March 22, 1904.

Application filed September 18, 1903. Serial No. 173,653. (No model.)

To all whom it may concern:

Be it known that I, WILLIAM H. SOLEY, a citizen of the United States, residing at Philadelphia, county of Philadelphia, and State of Pennsylvania, have invented a new and useful Improvement in Pneumatic Tools, of which the following is a full, clear, and exact description, reference being had to the accompanying drawings, which form a part of this specification.

I will first describe the embodiment of my invention illustrated in the accompanying drawings and then point out the invention in the claims.

15 Figure 1 is a section of my improved pneumatic tool on line 1 1, Fig. 6. Fig. 2 is a section of my improved pneumatic tool on line 2 2, Fig. 6. Fig. 3 is a view similar to Fig. 1 with valve and piston in opposite positions. 20 Fig. 4 is a view similar to Fig. 2 with valve and piston in opposite positions. Fig. 5 is a section on line 5 5, Fig. 2. Fig. 6 is a section on line 6 6, Fig. 2. Fig. 7 is a section on line 8 8, Fig. 2. Fig. 8 is a section on line 8 8, Fig. 2. Fig. 9 is a section on line 9 9, Fig. 6.

A is the casing, having the piston-chamber B and valve-chamber C. In the piston-chamber B is the piston D, and in the valve-chamber C is the valve E. This valve is a differential valve, the top surface e being smaller than the bottom surface e' . The valve E also has the passage e^2 through it, said passage e^2 being closed at the bottom with the exception of the small opening e^3 , which connects the 35 passage e^2 with the valve-chamber beneath the valve. From this portion of the valve-chamber a passage e^4 extends to the upper end of the piston-chamber. Through the valve at its lower end are orifices e^5 . When the valve 40 is in the position shown in Figs. 1 and 2, the live air is admitted to the valve from the source of pressure-supply through passage F into the passages G, leading to the bottom of the piston-chamber. When the valve is 45 in the position shown in Figs. 3 and 4, the orifices e^5 are in connection with passages e^7 , leading to the top of the piston-chamber.

f, f are orifices in the piston-chamber connecting with a cut-away portion f' , connected with an exhaust-opening through the casing. 50 H is the main exhaust. In the valve-casing are the annular passages h, h', h^2 , separated by flanges.

When the valve is in the position shown in Figs. 1 and 2, the annular passage h registers 55 with the passages I, terminating in the upper portion of the piston-chamber.

When the valve is in the position shown in Figs. 3 and 4, the annular passage h' registers 60 with passage G from the bottom of the piston-chamber.

Such being the construction, the operation is as follows: Taking the parts in the position shown in Figs. 1 and 2, the live air will pass through the passage G to the bottom of 65 the piston-chamber, moving the piston upward. The air in front of the piston will exhaust through the orifices f, f and through the passage I. Any air passing through the small opening e^3 and entering the piston-chamber through passage e^4 will exhaust 70 through the passage I and not affect the upward movement of the piston. When the piston has moved upward a distance sufficient to close the exhaust I and the passage e^4 , the 75 air passing through the opening e^3 will be trapped and exert a pressure upon the surface e' of the valve, which, being the portion of the valve of greater area, will cause the valve to shift to the position shown in Figs. 3 and 4. 80

When the parts are in the position shown in Figs. 3 and 4, the live air passes through the orifices e^5 into passages e^7 to the top of the piston-chamber and the piston tends to move downward. The air below the piston escapes 85 through the passages G, annular passage h' , and exhaust H.

Having now fully described my invention, what I claim, and desire to protect by Letters Patent, is—

1. In a pneumatic tool, in combination, a piston-chamber, a piston in said chamber, a valve-chamber, a valve in said chamber, said valve having pressure-surfaces of different 90

areas, a constant connection between the source of supply and the valve-chamber contiguous to the pressure-surface of greater area and a passage from that portion of the valve-chamber to the piston-chamber.

2. In a pneumatic tool, in combination, a piston-chamber, a piston in said chamber, a valve-chamber, a valve in said chamber, said valve having pressure-surfaces of different areas, a constant connection between the source of supply and the valve-chamber contiguous to the pressure-surface of greater area and a passage from that portion of the valve-chamber to the piston-chamber, adapted to be closed by the piston in its movement.

3. In a pneumatic tool, in combination, a piston-chamber, a piston in said chamber, a valve-chamber, a valve in said chamber, said valve having pressure-surfaces of different areas, an orifice through the pressure-surface of greater area, and a passage from the valve-chamber contiguous to said orifice extending to the piston-chamber.

4. In a pneumatic tool, in combination, a piston-chamber, a piston in said chamber, a valve-chamber, a valve in said chamber, said valve having pressure-surfaces of different areas, an orifice through the pressure-surfaces of greater area, and a passage from the valve-chamber contiguous to said orifice extending

to the piston-chamber, adapted to be closed by the piston in its movement.

5. In a pneumatic tool, in combination, a piston-chamber, a piston in said chamber, a valve-chamber, a valve in said chamber, said valve having pressure-surfaces of different areas, an orifice through the pressure-surface of greater area, the interior of the valve being in constant communication with the air-supply, and a passage from the valve-chamber contiguous to said orifice extending to the piston-chamber.

6. In a pneumatic tool, in combination, a piston-chamber, a piston in said chamber, a valve-chamber, a valve in said chamber, said valve having pressure-surfaces of different areas, an orifice through the pressure-surface of greater area, the interior of the valve being in constant communication with the air-supply, and a passage from the valve-chamber contiguous to said orifice extending to the piston-chamber, adapted to be closed by the piston in its movement.

In testimony of which invention I have hereunto set my hand at Philadelphia on this 15th day of September, 1903.

WILLIAM H. SOLEY.
